UNITED STATES PATENT OFFICE.

ALFRED MARQUIS AND HEINRICH HAHN, OF NEW YORK, N. Y.

PHYSICIAN'S MEDICINE-CASE.

SPECIFICATION forming part of Letters Patent No. 372,812, dated November 8, 1887.

Application filed March 27, 1886. Serial No. 196,868. (No model.)

To all whom it may concern:

Be it known that we, ALFRED MARQUIS and HEINRICH HAHN, of the city, county, and State of New York, have invented certain new and useful Improvements in Physicians' Medicine-Cases, of which the following is a specification.

This invention relates to a medicine-case for physicians, in which the rows of bottles in the same are supported in step shape one above the other when the case is opened, so that each bottle can be conveniently removed for use.

The invention consists in the construction and combination of parts and details, as will be fully described and set forth hereinafter, and finally be pointed out in the claims.

In the accompanying drawings, Figure 1 represents a plan view of our improved physician's medicine-case with the lid in open position. Figs. 2 and 3 are vertical transverse sections of the case on line $x-x$, Fig. 1, showing the same, respectively, in closed and open position; and Fig. 4 is a front elevation of the medicine-case drawn on a smaller scale.

Similar letters of reference indicate corresponding parts.

Our improved medicine-case consists of a body, A, that is provided with a hinged front, B, and a hinged lid, C, which are connected to each other by a suitable locking device. The inside of the hinged front B is supplied with suitable sockets, d , for a row of bottles, D, which are preferably the smaller bottles, while in the body A are supported, in a fixed and partitioned case, d' , a row of larger bottles, D', and back of the same are vertically-movable rows of bottles D'' D''' which are supported in partitioned cases $d'' d'''$. The hindmost case, d'' , is connected at both ends, by pivot-links e , with links e' , that are pivoted to lugs e'' of the lid C, so that when the lid is opened the case d'' and bottles D'' are lifted bodily, so as to project above the body A, as shown in Fig. 3, while when closing the lid C the case d'' and bottles D'' are lowered to their normal position in the body A, as shown in Fig. 2. The case d'' is connected, by horizontal strips f , that are attached to the end walls of the same and provided with hook-shaped ends f' , to the slotted end walls of the intermediate case, d' , so that when the hindmost row of bottles has been lifted to such an extent that the strips f ar-

rive at the upper end of the slots f'' of the case d' the latter and the bottles D'' are also raised to a certain distance from the bottom of the body A, and thus supported intermediate between the hindmost row and the fixed front row of bottles in such a manner that the rows are arranged in step shape one above the other, as shown in Fig. 3.

When the front of the case with its bottles is lowered and the lid opened, all are in full view, so that the labels can be easily read and any required bottle be readily removed for use. For closing the case, the front B is moved up again and the lid closed, whereby the hindmost row of bottles and then the intermediate row are lowered until the cases of the same arrive at the bottom of the body A, as shown in Fig. 2. When the case is opened, all the bottles in the same are arranged in rows, of which one row is above the other in the same manner as if they were arranged on shelves, whereby the bottles can be more conveniently handled and the compounding of medicines by the physician greatly facilitated.

We do not desire to claim, broadly, the combination, with the body of a medicine-case, of upwardly-movable bottle-trays arranged side by side, a hinged lid, and connections between the lid and one of the trays and between the tray and one or more other trays, whereby the opening or closing of the lid causes the successive rising or lowering of two or more of the trays.

Having thus described our invention, we claim as new and desire to secure by Letters Patent—

1. The combination, in a medicine-case, of a body, a row of bottles supported in a fixed case, an intermediate row of bottles supported in a movable case having slotted ends, a hindmost row of bottles supported in a case, said case having horizontal guide-strips that engage the slotted ends of the intermediate case, a hinged lid, and pivoted links by which the lid is connected to the hindmost case, so as to successively raise the hindmost and intermediate rows of bottles on opening the lid and arrange them in step shape above the fixed row of bottles, substantially as set forth.

2. The combination, in a medicine-case, of the body having a hinged front lid with bot-

tles supported at the inside of the same, a row of bottles supported in a fixed case, an intermediate row of bottles supported in a movable case having slotted ends, a hindmost row of 5 bottles supported in a movable case having guide-strips engaging the slotted ends of the intermediate case, a hinged lid back of the hindmost row, and pivot-links connecting the lid with the case of the hindmost row of bottles, substantially as set forth.

In testimony that we claim the foregoing as our invention we have signed our names in presence of two subscribing witnesses.

ALFRED MARQUIS.
HEINRICH HAHN.
